UNITED STATES PATENT OFFICE.

GUSTAV MONRATH, OF CHUQUICAMATA, CHILE, ASSIGNEE TO CHILE EXPLORATION COMPANY, OF NEW YORK, N. Y., A CORPORATION OF NEW JERSEY.

APPARATUS FOR LINING RESERVOIRS AND THE LIKE.

1,219,840.

Specification of Letters Patent.

Patented Mar. 20, 1917.

Application filed March 11, 1915. Serial No. 1,804.

To all whom it may concern:

Be it known that I, GUSTAV MONRATH, a citizen of the United States, residing at and whose post-office address is Chuquicamata, 5 Republic of Chile, South America, have invented certain new and useful Improvements in Apparatus for Lining Reservoirs and the like; and I do hereby declare the following to be a full, clear, and exact description of the invention, such as will enable others skilled in the art to which it 10 pertains to make and use the same.

My invention relates to improvements in apparatus for building up, supporting and 15 retaining, until set, mastic compounds applied in plastic condition to and serving as linings for large reservoirs.

The invention is particularly applicable to the lining of the inner sides of the walls 20 of large reservoirs used in the leaching of ores and in the electrolysis of the solutions thus obtained.

These reservoirs are built, *in situ*, of concrete, and are extensive substantial structures, 25 which, in their modern development, are usually sixteen or more feet in height, often covering acres of ground, so that the application thereto of the inner lining, which is required to protect them from the 30 corrosive action of the contents of the reservoirs, involves difficult engineering problems and considerations.

The mastic lining for these reservoirs is composed of tar, asphaltum or the like, 35 mixed with a suitable filler of crushed rock, pebbles or other appropriate material, and is applied hot, the bituminous material being in a plastic or semi-liquid condition.

Prior to my invention, so far as I am 40 aware, the only means which has been suggested or used for supporting and retaining the mastic material in position against the wall during its application thereto and its subsequent cooling and setting, comprised ordinary planking and framing.

With the use of wood for holding the hot mastic in position, owing to the absorbent character of wood and the moisture therein contained, blisters are formed on the exposed face of the mastic lining, to cover which it becomes necessary; after the mastic material has become cooled and set, to paint it with hot asphalt.

Another objectionable characteristic of 55 wood, when used for this purpose, is its rela-

tively low conductivity for heat, which requires the retention of the temporary support in its operative position for an extended period of time, to retain the mastic lining in proper form until it has become sufficiently hardened to be self-supporting. 60

The object of my invention is to provide an apparatus for building up, supporting and retaining the mastic lining, and which may be extended to any desired height and 65 length, which is adjustable to and from the wall to be lined, for obtaining a lining of the desired thickness, and which has a non-absorbent mastic supporting surface which possesses relatively high conductivity for 70 heat; thereby eliminating the formation of blisters on the exposed face of the lining, and which, by the quick radiation of the 75 heat, permits the lining to cool and to become hardened in a relatively short time so as to allow of the early withdrawal of the apparatus.

My invention provides further an apparatus adapted for ready assembling and disassembling, which will have a maximum of 80 strength and rigidity, while possessing relatively light weight, and in which the joints in the surface which supports the lining, will be close fitting and tight.

In the accompanying drawings, which 85 illustrate the preferred embodiment of my invention,

Figure 1 is a perspective view of my improved apparatus shown in operative position in a reservoir, a portion of which is 90 shown.

Fig. 2 is a view partly in side elevation and partly in vertical section of the apparatus shown in operative position and partly broken away.

Fig. 3 is an enlarged end elevation of one of the channel molding members and portions of the two adjacent molding members.

Fig. 4 is an end elevation of a bracing plate, such as is shown in Fig. 3.

Fig. 5 is a side elevation of another one of the bracing plates.

Fig. 6 is an end elevation of the bracing plate shown in Fig. 5.

Fig. 7 is a cross-section on the line 7-7 of Fig. 5.

Fig. 8 is an enlarged horizontal sectional view showing one of the vertical corner molding members and some of the side molding members which are attached thereto.

Fig. 9 is a perspective view of the left end of one of the channel molding members and the bracing plate, which is adapted to be secured therein, shown detached therefrom.

5 Fig. 10 is a side elevation of one of the adjustable clamps for holding down the molding members and for holding them secured to the scaffold.

10 Fig. 11 is a top view, partly broken away, of the clamp shown in Fig. 10, shown mounted on one of the vertical supports for the molding members.

15 Fig. 12 is an enlarged cross-section of one of the anchoring strips shown attached to the wall.

19 Similar reference characters designate similar parts in the different views.

For preparing the walls 1 of the reservoir to have applied thereto the mastic lining, 20 vertical anchoring strips 2, which are, preferably, V-shaped in cross-section, are secured by suitable devices, such as staples or wires 3, to the inner sides of the walls 1, the strips being spaced about two feet apart, 25 and the angles or ridges of the anchoring strips resting against the walls.

30 Suitable reinforcing and supporting material, comprising wire-netting, expanded metal, or other suitable foraminous material 4 is then secured to the outer edges of the strips 2. The material 4, together with the strips 2, serve as the permanent supports for holding the mastic lining secured to the walls 1. The strips 2 serve not only as supports for the reinforcing material 4, but, 35 by reason of their flanges flaring outwardly from the wall, they also serve directly as anchors for the mastic material. The strips 2, being disposed vertically, do not interfere 40 with the pouring of the mastic material in the formation of the lining.

45 For building up, retaining and supporting the mastic compound until it has become cooled and set, and for giving it the proper thickness, I provide a vertically and horizontally extensible wall, which is disposed parallel with the wall to be lined, and which is supported by a suitable framework,—preferably portable scaffolds which 50 are self-supporting, and which may be adjusted to any desired distance from the wall to be lined.

55 The extensible wall just referred to, and which serves as a form for one side of a mold for receiving the mastic material, is composed, preferably, of non-absorbent material, so as to avoid the formation of blisters on the exposed face of the mastic lining.

60 In the preferred form of my invention, this extensible wall consists of a plurality of sheet steel channel members, which are supported by scaffolds, hereinafter described, the channel members being provided with horizontal matched edges, where- 65 by the extensible molding wall has great

rigidity and the joints in the molding surface thereof are close fitting and tight.

Each channel molding member is provided with an upright molding wall 5, Fig. 9, and two horizontal inverted V-shaped flanges 6 and 7, disposed one upon the other, the upper flange serving as a roof, and being provided with a pouring incline 8, which inclines downwardly and inwardly toward the molding wall 5. The lower flange 7 serves as a base for the channel molding member, and has the same configuration as the flange 6, and is adapted to match with the roof flange 6 of the channel molding member next below.

80 In order to impart the requisite rigidity and strength to the channel molding member, it may have secured in it two or more bracing members 9 and 10, which are adapted to be respectively secured, by riveting or otherwise, in the right and left ends of the channel molding members, as shown in Fig. 8.

85 Each of the bracing members 9 and 10 is provided with flanged edges through which the rivets may pass which secure the bracing members to the channel molding members.

85 The channel molding members are disposed horizontally one above the other, as shown in Figs. 1 and 2, the lowermost channel member resting upon the concrete of the reservoir wall.

90 The channel molding members are retained in position by means of vertical supporting members 11, Figs. 1 and 2, against which the flanges 6 and 7 of the molding members rest.

95 The vertically supporting members 11 are releasably supported by and preferably spaced apart from a suitable supporting framework, preferably comprising portable self-supporting scaffolds.

100 In Fig. 1 two of these portable scaffolds are shown. They may be of any desired dimensions, and are of such number as is required by the inner dimensions of the reservoir which is to be lined.

105 Each scaffold is provided with a plurality of pairs of vertical timbers 12 and 13, the lower ends of which are secured to horizontal timbers 14, which are adapted to rest upon the floor 15 of the reservoir.

110 Connecting the members 12 and 13 of each pair of vertical timbers are transverse bars 16, which serve to brace the vertical timbers 12 and 13, and which also serve to support horizontal planks 17, which are adapted to support workmen. These planks may be elevated to different cross-bars 16 from time to time as the work progresses.

115 Oblique bracing timbers 18 are respectively secured to the vertical timbers 13 and to the horizontal timbers 14. Cross-braces 19 connect the vertical timbers 13.

120 The vertical supporting members 11 are

125

releasably supported on horizontal bolts 20, which extend through the vertical timbers 12. Removable spacing washers 21 encircle the bolts 20, and are disposed between the members 11 and the timbers 12.

For holding down the channel molding members 5, there are provided a plurality of U-shaped clamps, best shown in Figs. 10 and 11, the arms 22 of which embrace and 10 are vertically slidable on the vertical supporting members 11. One arm 22 of each clamp is provided with a transverse screw-threaded hole in which is fitted a thumb screw 23, which is adapted to bear against the adjacent member 11, for securing the clamp to the position in which it may be 15 adjusted.

The lower end of the transverse portion 24 of each of these U-shaped clamps is preferably provided with a V-shaped notch 25, Fig. 10, which is adapted to receive the upper edge of the uppermost channel molding member 5, as is shown in Figs. 1 and 2.

At the inside corners of the reservoir are 25 respectively provided corner members, to which the ends of the adjacent side molding members 5 are releasably secured. One of these corner members is shown in its operative position in Figs. 1 and 8. Preferably 30 each corner member is also a molding member and consists of a vertical curved sheet metal channel member 26, the longitudinal edges of which are provided with inwardly turned flanges 27, Fig. 8, which are secured 35 to the adjacent bracing plates 9 or 10, as the case may be, by ordinary screw clamps 28, of the usual U-form, one of the arms of which is adapted to bear against the inner side of the adjacent flange 27, and the other 40 arm of which has mounted in it a clamping screw 29, which is adapted to bear against the adjacent bracing plate 9 or 10 as the case may be.

Secured within each corner channel 26, at 45 spaced intervals apart, are bracing blocks 30.

In preparing for the application of the mastic lining for the inner walls of the reservoir, after the anchoring strips 2 have been secured thereto, and the reinforcing 50 material 4 has been secured to the strips, the portable scaffolds are positioned side by side and at proper distances from the concrete walls 1, following which the steel channel molding members 5 are arranged in 55 vertical and in horizontal series, as shown in Figs. 1 and 2, with their flanges resting against the vertical supporting members 11, the lowermost channel members resting upon the concrete at the bottom of the walls. A 60 sufficient space is provided between the channel molding members and the reinforcing material 4 for the reception of mastic material for the production of a lining of the desired thickness.

The clamps 22 are then adjusted vertically

on the supporting members 11 to positions in which the clamps will bear against the uppermost channel molding members which have thus been assembled. The thumb screws 23 are then tightened so as to hold the 70 clamps securely in the positions in which they have been adjusted.

The vertical corner members 26 are then mounted in their proper positions and are held secured to the bracing plates 9 and 10 75 of the channel molding members, by applying the screw-clamps 28, as has been herein-before described.

The series of channel molding members, thus assembled, extends clear around the 80 inner side of the reservoir, and is of a height such that the workmen standing on the floor of the reservoir may readily pour the mastic material over the uppermost molding member and into the space between the molding 85 members and the walls.

When found desirable the contiguous flanges 6 and 7 of the channel molding members, may be held clamped together by screw-clamps 31, which correspond in construction to the screw-clamps 28, which have already been described. Two of these clamps 31 are shown in operative position in Fig. 1.

The mastic compound α is then poured, in 95 its semi-liquid or plastic condition, into and filling the space between the molding members and the reservoir walls. The pouring incline 8 on the flanges 6 of the uppermost channels molding members 5 serve to guide 100 the mastic material and to prevent its being spilled during the pouring operation.

When the space between the reservoir walls and the molding members has been 105 filled with the hot mastic material, the material may be allowed to partially cool, when the clamps 22 may be removed, and another series of channel molding members may be assembled upon the series which has already 110 been assembled, following which the clamps 115 22 are again applied to the supporting members 11 and are arranged to bear against the uppermost molding members of the newly arranged series. The molding members of the new series are likewise secured by screw-clamps 28 to the flanges 27 of the corner molding members 26.

A fresh quantity of hot mastic material is then poured into and permitted to fill the space between the reservoir walls and 120 the newly arranged series of molding members.

The molding members are thus applied in consecutive series and the mastic material is poured into the space between the molding members and the reservoir walls, until a mastic lining has been applied to the entire inner sides of the reservoir wall.

As the vertical series of molding members increase in height, the planks 17 may 130

be adjusted vertically as the work demands and to suit the convenience of the workmen who stand upon these planks.

It will be understood that additional vertical corner members 26 may be assembled end to end upon those which have already been placed as may be required.

With the use of sheet steel in the construction of the molding members 5 and 10 their corner members 26, a molding surface is obtained which is non-absorbent, and which will, therefore, not contain any moisture or air, thereby eliminating the formation of blisters upon the exposed face of the 15 mastic lining, such as form when wood is employed to support and retain the hot mastic in place.

Sheet metal having a smooth surface permits the mastic material to readily slide 20 downwardly, so that the filling operation may be quickly and efficiently effected. To further facilitate the filling operation, and also to enable the molding members to be removed without any of the mastic material 25 adhering thereto, the molding surface may be coated with soft soap or a similar lubricating material.

As the channel molding members are made of a sheet metal which has relatively high 30 conductivity for heat, and as they may be relatively very thin and still, owing to their channel form, possess great strength and rigidity, the heat of the mastic lining will be quickly radiated through the molding members to the atmosphere. The mastic lining will, therefore, soon cool and harden, in 35 which condition it will be firmly held to the reservoir walls by means of the reinforcing material 4 and the anchoring strips 2, which 40 will be embedded in and entirely covered and inclosed by the mastic material.

After the mastic material has hardened sufficiently the molding members and the scaffolds may be removed. To effect this, 45 the thumb-screws 23 are loosened, and the clamps 22, 28 and 31 are removed from their operative positions. The bolts 20 are then withdrawn from the vertical members 11, thereby permitting the removal of the spacing washers 21, after which the vertical 50 supporting members 11 may be removed from their operative positions, thereby permitting the ready dis-assembling and removal of the channel molding members 5 and 26.

As the roof and base flanges 6 and 7 of the channel molding members 5 respectively match with the base and roof flanges of the adjacent molding members, the joints between said members are close fitting and 60 tight, and a very rigid molding wall is thereby obtained.

As usually employed by me, the channel molding members are about eight feet long 65 and six inches wide on the molding face.

The height of the portable scaffold is such as will suit them for the work in hand. Usually the reservoir walls 1 are sixteen or more feet in height, and in such case these scaffolds are made of a corresponding or 70 slightly greater height.

For cross-bracing the portable scaffold, transverse bracing bars 32 and 33 may be secured respectively to the uppermost cross-bars 16 and to the horizontal bars 14, as 75 shown in Fig. 1.

I do not limit my invention to the structure shown and described, as modifications, within the scope of the appended claims, may be made without departing from the 80 spirit of my invention.

Having thus described my invention, what I claim and desire to secure by Letters Patent, is:

1. A temporary structure of the class 85 described, comprising upright supporting members, horizontal limiting members supported thereby, said horizontal members being adapted to be introduced upon each other from above, and provided with complementary backwardly projecting flanges, whereby the adjacent members may be clamped together, said flanges being shaped to interfit when placed one on top of the other.

2. A temporary structure for the purpose 95 specified, comprising upright supporting members and horizontal limiting members supported thereby, said horizontal members having complementary backwardly projecting flanges of V-shaped cross-section, adapted 100 to interfit when placed one on top of the other, and affording means for clamping the adjacent horizontal members together.

3. A temporary structure for the purpose specified, comprising upright supporting 105 members and horizontal limiting members supported thereby, together with means for retaining the horizontal members in their proper position, said means being adjustable on said upright members and arranged 110 to engage said upright members in position above the horizontal members, and hold the latter against the upright members.

4. A temporary structure for the purpose specified, comprising upright supporting 115 members and horizontal limiting members supported thereby, together with retaining blocks, and means for setting the blocks on said upright members in position to retain the horizontal members in their proper position, the lower surface of said retaining blocks being cut to engage the top of the horizontal members, and hold them against the upright members.

5. An apparatus for molding linings of 125 the kind described, comprising a scaffold, and molding members adapted to be supported horizontally thereby one upon the other and having matched upper and lower edges, the upper edge of each of said mem- 130

bers inclining downwardly and inwardly toward the molding surface.

6. An apparatus for molding linings of the kind described, comprising a scaffold, a plurality of molding members adapted to be supported horizontally thereby one upon the other, releasable means for clamping the molding members to each other, and means for holding the top member against and supported by the scaffold.

7. An apparatus for molding linings of the kind described, comprising a scaffold, a plurality of molding members adapted to be supported horizontally thereby one upon the other and having bent and matched upper and lower edges, releasable means for clamping the molding members to each other and means for holding the top member against the scaffold.

8. An apparatus for molding linings of the kind described, comprising a scaffold, vertical members releasably secured thereto, molding members adapted to be supported horizontally one upon the other against said vertical members, means for clamping said molding members to each other and means for holding the top member against said vertical members.

9. An apparatus for molding linings of the kind described, comprising a scaffold, vertical members releasably secured thereto, spacing devices releasably held between the scaffold and said vertical members, a plurality of molding members adapted to be supported horizontally one upon the other by said vertical members, releasable means for clamping said molding members to each other and means for holding the top member against said vertical member.

10. An apparatus for molding linings of the kind described, comprising a scaffold, vertical members releasably secured thereto, a plurality of molding members disposed horizontally one upon the other and adapted to be supported by said vertical members whereby the vertical supporting members may be removed independently of the molding members, and clamping means for securing said molding members against each other.

11. An apparatus for molding linings of the kind described, comprising a scaffold, vertical supporting members, bolts for releasably securing said vertical members to said scaffold, a plurality of molding members adapted to be supported one upon the other by said vertical members and having matched upper and lower edges, whereby the vertical supporting members may be removed independently of the molding members, means for releasably clamping the molding members to each other and means for holding the top member against said vertical members.

12. An apparatus for molding linings of

the kind described comprising a scaffold, vertical members releasably secured thereto, a plurality of sheet metal channel molding members adapted to be supported horizontally one upon the other and to rest against said vertical members and having matched upper and lower edges, and means vertically adjustable on said vertical members for releasably engaging and holding the uppermost molding members, said matched upper and lower edges being so conformed that the means last mentioned by holding the uppermost molding members against the vertical members also hold the other molding members against the vertical members.

13. In an apparatus for molding linings of the kind described, a form composed of a plurality of molding members each having an upright molding wall, and provided with a roof having a pouring incline, and a base of the same configuration as the roof, the base being adapted to match with the roof of a similar form.

14. In an apparatus for molding linings of the kind described, a plurality of molding members of channel form, each having the bottom of the channel serving as an upright molding wall, one of the flanges of the channel serving as a roof and having on its upper side a pouring incline, and the other flange of the channel having the same configuration as the roof flange, and being adapted to match with the roof flange of a similar member.

15. In an apparatus for molding linings of the kind described, a sheet metal molding member having an upright molding wall, and provided with a roof having a pouring incline, and a base of the same configuration as the roof, the base being adapted to match with the roof of a similar member.

16. In apparatus for molding linings of the kind described, a sheet metal unit of approximate channel form, the flanges of the channel having in cross-section a V-shape, one being convex and the other concave, and being arranged so that the flange of one unit will interfit with the flange of an adjacent unit.

17. In an apparatus for molding linings of the kind described, a plurality of non-absorbent molding members adapted to be arranged horizontally one upon the other and having matched upper and lower edges, the upper edge of each member having a pouring incline.

18. In an apparatus for molding linings of the kind described, molding members disposed horizontally one above the other and having matched upper and lower edges, each member having an upright molding wall and a roof having a pouring incline, a vertical corner member, and means for releasably securing the corner member to the molding members.

19. In an apparatus for molding linings of the kind described, channel molding members arranged horizontally one upon the other, the bottom of the channel of each member being disposed vertically and serving as a molding wall, the flanges of each channel member being disposed horizontally one above the other and respectively matching with adjacent flanges of the adjacent molding members, the upper flange of each member having on its upper side a pouring incline, a vertical corner member, and means for releasably securing the corner member to the molding members.
- 15 20. A temporary structure for the purpose specified, comprising upright supporting members, and horizontal limiting members supported thereby; said horizontal members being adapted to be introduced upon each other from above and provided with backwardly projecting flanges, certain of said flanges being horizontally arranged and shaped to interfit when placed one on top of another and certain of said flanges being vertically arranged, whereby the adjacent members may be clamped together by way of said flanges thus to establish a wall readily extended at will both vertically and horizontally.
- 30 21. A temporary structure for the purpose specified, comprising upright supporting members, and horizontal limiting members supported thereby; said horizontal mem-

bers being adapted to be introduced upon each other from above and provided with 35 backwardly projecting flanges, certain of the limiting members having plane limiting walls, and certain of said members having curved limiting walls, the former limiting members having horizontally arranged 40 flanges shaped to interfit when placed one on top of another, and all the limiting members having vertical flanges, whereby adjacent members may be clamped together by way of said flanges to establish a wall which, 45 while turning a corner, is readily extended both vertically and horizontally at will.

22. In apparatus for molding linings of the kind described, a horizontally elongated molding unit having a vertically arranged 50 molding wall and backwardly extending top and bottom flanges so arranged that the bottom flange of one unit will interfit with the top flange of a lower unit; each flange having substantially the cross-section of an inverted V with one leg of the V considerably shorter than the other so that the latter may establish a pouring incline almost as wide as the flange.

In testimony whereof I affix my signature, 60 in presence of two witnesses.

GUSTAV MONRATH.
